(57) **CLAIM**

We claim the ornamental design for an eyewear component, as shown and described.

DESCRIPTION

FIG. 1 is a front perspective view of eyewear and the eyewear component of the present invention;

FIG. 2 is a front elevation view thereof;

FIG. 3 is a left-side elevation view thereof, the right-side elevation view being a mirror image thereof;

FIG. 4 is a rear elevation view thereof;

FIG. 5 is a top plan view thereof; and,

FIG. 6 is a bottom plan view thereof.
